EXERCISER AND LEG REST

Philip F. Roberge, Wethersfield, Conn.

Application May 27, 1949, Serial No. 95,672

5 Claims. (Cl. 272—57)

1

The invention relates to an exerciser and leg rest adapted for use by patients having certain leg disorders such as those resulting from diabetic or arterio-sclerotic tendencies or such as those resulting from varicose veins.

In the treatment of patients such as those above-mentioned, it is recognized practice to elevate the legs of the patient to a substantial extent so that stagnant blood will flow therefrom, this stagnant blood being replaced by fresh blood when the legs are lowered. This procedure is ordinarily followed with the patient in bed, a frame or board being usually provided which rests on the bed for supporting the patient's legs in the elevated position. The raising of the legs with the patient in prone positions causes a rush of blood to the head, this tending to exhaust the patient and being otherwise detrimental.

In accordance with the invention I provide an exerciser and leg rest which can be placed on the floor and which can be used by a patient comfortably seated in a chair. This makes it possible for the legs to be substantially raised without being raised above the level of the patient's head. The exerciser and leg rest has groups of leg supports so arranged that the legs of the patient can be supported at various selected elevations and further so arranged that the patient can conveniently move his legs to or from the selected positions through a series of successive stages. By reason of the provision for successive stages of movement, the patient is able to readily move his legs to and from positions that he could not otherwise attain. Furthermore, the patient in so moving his legs exercises them in a manner producing favorable results.

The invention further relates to various details of structure whereby the foregoing more general purposes are simply and economically attained.

In the drawing I have shown in detail a preferred embodiment of the invention, but it will be understood that various changes may be made from the construction shown, and that the drawing is not to be construed as defining or limiting the scope of the invention, the claims forming a part of this specification being relied upon for that purpose.

Of the drawing:

Fig. 1 is a perspective view illustrating the manner of use of an exerciser and leg rest embodying the invention.

2

Fig. 2 is a front view of the exerciser and leg rest.

Fig. 3 is a side view.

Fig. 4 is an enlarged fragmentary vertical sectional view taken along the line 4—4 of Fig. 2.

As illustrated in the drawing, the exerciser and leg rest includes a frame adapted to rest on a floor. The frame preferably comprises an upright portion 10 which includes two horizontally and transversely spaced upright bars 12 and 14. An unobstructed space is provided at least at one side of the upright frame portion 10, that is, at the side toward the user which will be designated as the front side. Preferably and as shown, unobstructed spaces are provided at both sides of the upright frame portion 10, that is, at the front and rear sides thereof. The upright bars 12 and 14 are preferably rigidly connected at their respective lower ends with two transversely spaced longitudinally extending horizontal floor engaging bars 16 and 18. An unobstructed space is preferably provided between the floor engaging bars 16 and 18 at least at the unobstructed side of the frame portion 10, that is, at the front side thereof.

While the invention is not necessarily so limited, the two upright bars 12 and 14 may conveniently be parts of a structure in the form of an inverted U, this structure having a portion or bar 20 connecting the upper ends of the two upright bars 12 and 14. In order that the weight may be at a minimum the bars of the U-shaped structure and floor engaging bars may be tubular, and they are so shown.

Carried by the frame portion 10 are two groups of vertically spaced transversely extending substantially horizontal leg supports. The number of supports may be varied but as illustrated there are three supports in each group, the supports being arranged in pairs. The supports are respectively designated 22, 24, 26, 28, 30 and 32. The several leg supports are carried by and project from the upright portion of the frame and they are oppositely disposed with respect to a longitudinal vertical plane through the upright portion of the frame, the said plane being indicated at a—a in Fig. 2. Each leg support is relatively short and has an unobstructed space beyond and immediately adjacent its projecting end. The supports in the respective groups and in the respective pairs preferably extend toward each other with the inner ends of the supports in the respective groups and pairs spaced horizontally from each other so as to provide an unobstructed space between them. Preferably and

as shown, the several supports in the respective groups and in the respective pairs have the same lengths and are at the same levels and are in alignment with each other.

When the frame includes upright bars such as 12 and 14 the supports in the two groups are carried respectively by the two upright bars. Each support is connected at its outer end with the corresponding upright bar and extends inwardly therefrom. Preferably a horizontal cross bar 34 extends between the upright bars 12 and 14 being positioned below the lowermost supports 22 and 24. The cross bar provides mechanical connection between the upright bars to give increased strength and it may also serve as an additional leg support. The spacing between the cross bar 34 and the supports 22 and 24 may be the same as that between each two superposed supports.

Preferably, as more clearly shown in Fig. 4, each leg support in the two said groups comprises a core 36 of metal or other rigid material and a cushion 38 of soft resilient material, such as sponge rubber. The outer end portion of each core 36 extends into and through an aperture in the corresponding upright bar 12 or 14, being held in place by riveting or otherwise. Each cushion 38 has at least a portion thereof above or at the upper side of the corresponding core 36. As shown, the cushion entirely surrounds the core, and has a portion at the inner end which covers the inner end of the core. A cushion 40 similar to the cushions 38 may extend throughout the entire length of the cross bar 34.

Preferably the leg supports in the two groups, instead of being located in a vertical plane, are located approximately on arcs extending in longitudinal planes perpendicular to the supports. This facilitates the use of the supports by the patient as will be explained in detail. When the supports are carried by upright bars such as 12 and 14, the said upright bars are curved in longitudinal planes perpendicular to the direction of transverse spacing between them, that is, in planes perpendicular to the supports in the two groups.

The relative positions of the several leg supports will be more clearly understood by defining their relationship with respect to an arbitrarily selected vertical transverse reference plane such as *b*—*b* which is indicated in Fig. 3. The plane *b*—*b* is at the unobstructed side of the frame portion 10, that is, at the front side thereof. Each support of each group below the uppermost support of the said group is spaced from the reference plane *b*—*b* by a distance substantially greater than the distance of the next higher support from the said reference plane. The center lines of the uppermost supports 30 and 32 are at a distance *c* from the reference plane *b*—*b*, the center lines of the next lower supports 26 and 28 are at a greater distance *d* from the reference plane *b*—*b*, and the center lines of the next lower supports 22 and 24 are at a still greater distance *e* from the reference plane *b*—*b*. Preferably the center lines of the supports in each group are located substantially in a circular arc having its center at the unobstructed side of the frame. When a cross bar such as 34 is provided, its center line is at a distance from the said reference plane *b*—*b* which is at least as great as the distance *e* of the center lines of the lower supports 22 and 24 from the said reference plane.

In order that the exerciser and leg rest may be more conveniently shipped and stored, the several parts thereof are by preference detachably connected with each other. The details of detachable connection may be widely varied, but one suitable construction is illustrated.

Each of the floor engaging bars 16 and 18 has an upwardly extending tubular member 42 secured thereto by welding or otherwise. Each of the upright bars 12 and 14 has a plug 44 secured in place in the lower end thereof, and this plug fits into the upper end of the corresponding member 42. Set screws 46 hold the plugs 44 in place in the members 42. The upright bars 12 and 14 are thus connected with the bars 16 and 18, but are readily detachable when the set screws 46 are loosened.

The inverted U-shaped structure, which includes the tubular upright bars 12 and 14 and the connecting portion or bar 20, is preferably formed in three parts detachably connected with each other at the tops of the uprights. As shown, each end of the bar 20 has a plug 48 secured in place therein and these plugs fit into the upper ends of the upright bars. Set screws 50 hold the plugs in place in the uprights. The bar 20 is thus connected with the upright bars but is readily detachable when the set screws are loosened.

When a cross bar such as 34 is provided, it has reduced end portions which extend through pairs of opposite holes in the upright bars 12 and 14. The said reduced end portions are threaded and are engaged by nuts 52 which detachably hold the cross bar in place. If desired there may be a plurality of pairs of holes 54, 54 in the upright bars so that the cross bar 34 may be located at different elevations.

With the exerciser and leg rest disassembled for shipping or storage it comprises six units which are: the two upright bars 12 and 14 with the supports carried thereby, the two floor engaging bars 16 and 18 with the attached members 42, the connecting bar 20 and the cross bar 34 with its nuts 52.

In use the exerciser and leg rest is placed on the floor in proper relationship to the chair or other seat occupied by the patient. The unobstructed front side faces the chair. The patient can place his legs on any of the several supports that may be selected, his legs being moved upward, one at a time, through the unobstructed spaces between the supports. Preferably, the backs of the patient's ankles or heels engage the supports, the cushions of the supports serving to distribute the pressure and to avoid any discomfort.

The patient's legs move about a transverse axis approximately at his hip joints, and it will be clear that, if the several supports were in a vertical plane, the several supports would engage the patient's legs at different positions. In order that the several supports may engage the patient's legs at approximately the same positions, that is, at the ankles or heels, the supports are located on arcs or at different distances from the reference plane *b*—*b* as already described.

As shown in Fig. 1, the legs of the patient are at the same level on the pair of supports 26 and 28, but they may be at different levels on selected supports at different levels. Even when the patient's legs are on the uppermost supports 30 and 32, they are at a level no higher than the patient's head.

It is unnecessary for the patient to raise his legs by single movements to the selected sup-

ports, and he can raise them one at a time to the selected supports by successive stages. For instance, the patient may initially place his right ankle or heel on the cross bar or support 34 as indicated by dotted lines at A, and then move it successively to the support 24 as indicated by dotted lines at B, to the support 28 as indicated by full lines at C, and to the support 32 as indicated by dotted lines at D. The spaces between the inner ends of the supports are unobstructed and are sufficiently wide to freely permit movement as described. The cushions 38 extend over the ends of the cores 36 of the supports, thus preventing any bruises or abrasions such as might result from contact of the patient's ankles with the rigid cores.

The left leg may be similarly raised by successive stages. In practice, it is ordinarily preferable for the patient to raise both legs to one level before moving either leg to the next higher level. The patient may rest to whatever extent may be necessary or desirable between successive movements. By a reversal of the described stages, the patient may lower his legs as desired.

The unobstructed space between the front portions of the bars 16 and 18 avoids any interference with the chair and enables the patient's feet to freely engage the floor prior to and following the use of the apparatus.

The patient can repeatedly move his legs upward and downward by successive stages to and from selected elevated positions, as instructed by his doctor. His legs can be maintained at the highest selected elevation or at intermediate elevations for various periods of time as may be prescribed. The successive positioning of the patient's legs at higher and lower elevations improves circulatory conditions as described, and furthermore the upward and downward movements provide beneficial muscular exercise.

The treatment of a patient as described, using an exerciser and leg rest embodying the invention, has many advantages over the before-mentioned conventional treatment. This conventional treatment usually involves the well-known "Buerger's exercise and board" and this can be used only with the patient on a bed or couch. While there are objections to the raising and lowering of the legs with the patient in prone position, another serious disadvantage is the ability or disinclination of the patient to follow a treatment which involves the use of a bed or couch. Frequently no bed or couch is available in or near the living room and the patient is unwilling or perhaps unable to move to a bedroom which may be on another floor. Furthermore, the stand or board must be placed on the bed and removed therefrom, thus involving considerable trouble and effort.

The exerciser and leg rest embodying the present invention can be used wherever a chair or other convenient seat is available, and by reason of the fact that it stands on the floor it can be readily moved to and from the required position without any lifting. It can be kept in the living room and used frequently as prescribed.

It will be understood that masculine pronouns are used herein in a generic sense and not in a restrictive sense.

What I claim is:

1. An exerciser and leg rest comprising in combination, a frame including a generally upright portion with an unobstructed space at one transversely extending side thereof which frame portion comprises two transversely spaced upright

bars, the said frame also including two transversely spaced longitudinally extending horizontal floor engaging bars to which the respective upright bars are rigidly connected at their lower ends which floor engaging bars have an unobstructed space between them at the aforesaid unobstructed side of the upright portion, and two groups of vertically spaced transversely extending substantially horizontal leg supports carried by and projecting from the respective bars of the said upright portion of the frame, the supports of the two groups projecting in opposite directions and toward each other with unobstructed spaces between their projecting ends and each support of each group below the uppermost support of the said group being spaced from a vertical transverse reference plane at the unobstructed side of the upright portion of the frame by a distance substantially greater than the distance of the next higher support from the said reference plane.

2. An exerciser and leg rest as set forth in claim 1, wherein the upright bars are detachably connected with each other and are detachably connected respectively with the said floor engaging bars.

3. An exerciser and leg rest comprising in combination, a frame including a generally upright portion with an unobstructed space at one transversely extending side thereof which frame portion comprises two transversely spaced upright bars, the said frame also including two transversely spaced longitudinally extending horizontal floor engaging bars to which the respective upright bars are rigidly connected at their lower ends which floor engaging bars have an unobstructed space between them at the aforesaid unobstructed side of the upright portion, two groups of vertically spaced transversely extending substantially horizontal leg supports carried by and projecting from the respective bars of the said upright portion of the frame, the supports of the two groups projecting in opposite directions and toward each other with unobstructed spaces between their projecting ends and each support of each group below the uppermost support of the said group being spaced from a vertical transverse reference plane at the unobstructed side of the upright portion of the frame by a distance substantially greater than the distance of the next higher support from the said reference plane, and a horizontal transverse cross bar connecting the said upright bars below the lowermost leg supports in the two groups and above the floor engaging bars and providing an additional leg support, the said cross bar being spaced from the said vertical reference plane by a distance at least as great as the distances of the lowermost leg supports in the two groups from the said plane.

4. An exerciser and leg rest comprising in combination, a frame including a base having transversely spaced floor engaging portions in a common horizontal plane and also including a generally upright portion consisting of an inverted U in fixed relationship with the base and having a completely unobstructed space at one transversely extending side thereof so that a patient may be positioned therein and between said spaced floor engaging portions, which upright portion has two transversely spaced upright bars, two groups of vertically spaced transversely extending substantially horizontal leg supports carried by and projecting from the respective bars of the said upright portion of the frame, the

supports of the two groups projecting in opposite directions and toward each other a distance to provide therebetween unobstructed spaces between their projecting ends of sufficient magnitude to enable the legs of the patient to pass therethrough, and each support of each group below the uppermost support of the said group being spaced from a vertical transverse reference plane at the unobstructed side of the upright portion of the frame by a distance substantially greater than the distance of the next higher support from the said reference plane, and a horizontal transverse cross bar connecting the said upright bars below the lowermost leg supports in the two groups and providing an additional leg support, the said cross bar being spaced from the said vertical reference plane by a distance at least as great as the distances of the lowermost leg supports in the two groups from the said plane, said upright bars being bent in longitudinal planes perpendicular to said floor engaging

portions with the upper portions thereof being spaced from the vertical transverse reference plane at the unobstructed side of the upright portion a distance less than the distance of the lower portions thereof.

5. An exerciser and leg rest as set forth in claim 4 wherein there are at least three supports in each group and wherein the center lines of the supports in each group are located substantially in a circular arc having its center at the 10 unobstructed side of the frame.
